UNITED STATES PATENT OFFICE.

RANDOLPH HERSEY, OF MONTREAL, QUEBEC, CANADA.

NAIL-PLATE FEEDER.

SPECIFICATION forming part of Letters Patent No. 354,980, dated December 28, 1886.

Application filed October 11, 1886. Serial No. 215,659. (No model.)

To all whom it may concern:

Be it known that I, RANDOLPH HERSEY, of the city of Montreal, in the district of Montreal and Province of Quebec, Canada, have 5 invented new and useful Improvements in Nail-Plate Feeders; and I do hereby declare that the following is a full, clear, and exact description of the same.

This invention has reference to the construction and arrangement of a mechanism for presenting the plate from which pieces are cut by a nail-cutting machine (or by a nail-blank-cutting machine) to the cutters of the said machine.

15 The mechanism forming my present invention is arranged to present the nail-plate to the cutters of the nail or nail-blank cutting machine at the proper angle, after which it automatically draws back the plate and raises it, 20 turns it over, lowers the plate, and again presents it to the cutters of the nail-cutting or nail-blank-cutting machine.

25 My invention also provides that the feeding motion of the nail-plate will stop when the nail-plate has been cut down as close as may properly be to the nipper-rod or tongs by which it is held, and other features, which will be hereinafter set forth.

30 The particular combinations of features or elements which form my present invention will be hereinafter fully set forth and claimed.

In the drawings hereunto annexed similar letters of reference and numerals indicate like parts.

35 Figure 1 is a side elevation of a machine embodying my invention, shown in connection with a diagram of the principal parts of a nail-cutting machine to which it is connected. Fig. 2 is a diagram showing the motions of some of 40 the principal parts forming the mechanism embodying my invention, as shown in Fig. 1. Fig. 3 is a side elevation, part in section, showing the mechanism embodying my invention in the position presenting the nail-plate to the 45 cutters of the nail-cutting machine. Fig. 4 is a plan of the mechanism shown in Fig. 3. Fig. 5 is a longitudinal section taken on line $x x$, Fig. 4, showing also the nipper-rod or tongs for holding the nail-plate, which are omitted 50 in Fig. 4. Fig. 6 is a section on line $y y$, Fig. 5. Fig. 7 is an inner side elevation of the rack-

lever i' . Figs. 8 and 9 show modifications of one end of the rack-lever i' . Fig. 10 is a plan of the rest g^2 for carrying the slide l^2 . Fig. 10^a is a section on line $y y$, Fig. 10. Fig. 11 is a 55 section on line $x x$, Fig. 10, showing also the section of the nipper-rod or tongs in position in relation therewith. Fig. 12 is a front elevation of the slide l^2 , carried in the rest g^2 , shown in Fig. 10. Fig. 13 is a plan of the slide 60 shown in Fig. 12, part in section, the sectional part being taken on line $x x$, Fig. 12. Figs. 14, 15, and 16 are details of construction and arrangement of spring and followers. Fig. 17 is a section on line $x x$, Fig. 13. Fig. 18 is a 65 plan of the pawls by which the nipper-rod or tongs are operated. Fig. 19 is a plan of the nipper-rod or tongs. Figs. 20, 21, and 22 are modifications of the cam formed on the front end of the lever i' , Fig. 22 being a section on 70 line $x x$, Fig. 20.

Letter a is the bed of an ordinary nail-cutting machine. b is the driving-shaft; c , the cutting jaw, carrying the moving cutter d . e is the rest carrying the bed or stationary cutter f . (See Figs. 1 and 3.) All these parts are arranged in the ordinary manner.

On the driving-shaft b is secured a pinion, g , intermeshing with a gear-wheel, h , the pinion being half the diameter of the gear-wheel 80 h , so that the wheel h will make but one revolution to two of the pinion g . To the wheel h is attached an adjustable pin, i , to which is attached the connecting-rod k , the lower end of which is attached to a lever, l , carried in 85 a bracket, m , attached on the under side of the frame a , the whole being arranged so that the lever l will make one vibration to each cut of the cutter d , which cuts off pieces from the nail-plate.

90 All the above-described parts are arranged in a similar manner to that which has been in use prior to my present invention.

To the under side of the frame a , and at the front end thereof, is attached a sub-frame, n . 95 This is attached by two bolts, one passing through a circular opening, o , and the other through an elongated opening, p . (See Fig. 4.) This is for the purpose of enabling the necessary amount of adjustment of the angle 100 at which the nail-plate is presented to the cutters, and gives the desired width of point to

the nail. The frame n , being pivoted on the bolt passing through the opening o , rotates a small amount thereon that it is allowed by the length of the opening p .

5 On the frame n is formed a bracket, q , made integral with the frame n , or attached separate, as desired. On the frame n is formed an ordinary bearing, r , carrying an ordinary rock-shaft, s .

10 To the bracket q is pivoted, by the pivot t , the arm u of a swinging frame, a' . At the rear or back end of the swinging frame is formed a bearing, b' , for holding a revolving cylinder, c' . The rear end of the cylinder is provided 15 with an ordinary nose-piece, d' , similar to those at present in use in automatic mechanisms for presenting nail-plates to nail-cutting machines, and therefore need not be more particularly described.

20 The front end of the cylinder c' is provided with beveled teeth e' , forming it into a beveled gear-wheel. These teeth e' intermesh with similarly-beveled teeth f' , formed on a segmental rack, h' , made integral, preferably, 25 with the lever i' , pivoted on a double eye or bracket, k' , formed on the swinging frame a' by the pivot-pin l' . The lever i' extends beyond the pivot-pin l' , and on its front extremity is formed a segment, m' , provided with a 30 cam projection, n' , which will be hereinafter more particularly described.

At the front end of the lever l is attached a pin, o' , preferably in a slotted hole, for the purpose of allowing for adjustment. To the 35 pin o' is attached the lower end of a connecting-rod, p' . The upper end of the connecting-rod p' is attached to a pin, q' , on the segmental rack h' of the lever i' . By this arrangement, as the lever l is vibrated by the connecting- 40 rod k and pin i on the gear-wheel h the extent indicated by the dotted, solid, and chain lines 1 in the diagram Fig. 2, this causes the connecting-rod p' to move the extent indicated by the dotted, solid, and chain lines 2, causing 45 the lever i' to vibrate the extent indicated by the dotted, solid, and chain lines 3, from which it will be understood how the lever i' is operated.

In the lever i' is secured in a slot-opening, 50 r' , a pin, s' , thereby allowing for a certain amount of adjustment of the position of the pin s' . The pin s' is connected by a connecting-rod, t' , to the pin u' of an arm, v' , of the rock-shaft s .

55 On the under side of the swinging frame a' is formed an eye, a^2 , to which is connected by a pin, b^2 , the connecting-rod c^2 , the lower extremity of the connecting-rod c^2 being attached to the pin d^2 of the arm e^2 of the rock-shaft s . 60 By this arrangement the motion which is imparted to the lever i' , as hereinbefore described, and the extent of which is represented by the lines 3, Fig. 2, causes the connecting-rod t' to move the extent indicated by the lines 65 4, causing the arm v' of the rock-shaft s to vibrate the amount indicated by the lines 5 and the arm e^2 to vibrate the amount indi-

cated by the three lines 6. This causes the connecting-rod c^2 to move the extent indicated by the lines 7, causing the frame a' to swing 70 upon the pivot t , the position of which is indicated in Fig. 2 by the point t , thereby moving the center line of the frame a' and parts attached to or on it the extent that the line 8 (which is also one of the lines 3) is from the 75 line 9. From the position of the pivot t the action of the arm e^2 and connecting-rod c^2 not only causes an oscillating motion up and down of the frame a' , but also causes a backward and forward motion of the swinging frame a' , 80 which is indicated by the difference of position of the points 10 and 11 in Fig. 2, which points represent the center of the pin l' .

It will be observed that while the arm e^2 is shown in three positions, 6, only two positions, 85 12 and 13, of the pin b^2 result therefrom, and the position of it caused by the action of the rock-shaft arm e^2 and connecting-rod c^2 upon the swinging frame a' , because when the rock-shaft arm e^2 is in the central position of the 90 positions 6 the center of the pin b^2 is raised and moved forward to the position 12, while at the extremities of the movements of the rock-shaft arm e^2 the pin b^2 is lowered and brought backward at both extremities of the 95 movement to the position 13, and so with every portion of the frame a' and parts attached thereto. I wish to call particular attention to this last above-mentioned movement, because each time the center of the pin b^2 is 100 brought to the position 13 the nail-plate is presented to the cutters (and a piece cut off to be formed into a nail) in the manner which will be hereinafter described.

From the above description it will be understood that each time the lever l makes a complete vibration the cylinder c' is caused by the segmental rack h' to make an exact half-revolution, bringing at each extremity of said half-revolution the nail-plate f^2 to the position 110 shown in Figs. 3 and 4, while at the midway position of the vibrations the nail-plate f^2 will be in the position indicated in Fig. 1.

On the front end of the swinging frame a' is secured the rest g^2 by bolts h^2 . The rest g^2 115 consists of a bed, i^2 , provided with a dovetailed recess, k^2 , suitable for receiving the slide l^2 . (Shown in Figs. 12 and 13 on a somewhat larger scale.) This bed i^2 is made integral with a head, m^2 , provided with projections n^2 , in 120 which are formed recesses for holding the springs o^2 and heads p^2 . The springs o^2 , as shown, consist of rubber cushions. The inner surfaces of the heads p^2 project slightly into the space q^2 between the projections n^2 . 125 This space is so arranged that it will be central with the center line of the cylinder c' , and the heads p^2 will be arranged to grip tightly between them such portion of the body of the nipper-rod or tongs r^2 , situated between them, 130 in the manner hereinafter mentioned.

s^2 are cover-plates secured on the projections n^2 for keeping the springs o^2 and heads p^2 in place.

The slide l^2 consists of a plate dovetailed and recessed, as shown by the cross-section given of it in Fig. 11 and by the longitudinal section in Fig. 17. (See also front elevation and 5 plan in Figs. 12 and 13.) In the slide l^2 a recess, a^3 , is formed, in which are situated the follower-blocks b^3 c^3 and the spring d^3 . The recess a^3 extends from the front end of the slide l^2 , as shown, so that the follower-block c^3 is 10 pressed by the spring d^3 against the end of a set-screw, e^3 , screwed into a plate, f^3 , secured on the front end of the rest g^2 in an ordinary manner, so that the action of the spring tends to push the slide l^2 backward, and by the adjustment of the screw e^3 the action or pressure 15 of the spring d^3 may be increased or diminished.

On the front portion of the slide l^2 a projection, g^3 , is formed, in which is secured a pin, 20 h^3 , encircled by a thimble or bush, i^3 , which forms a roller to roll upon the periphery of the segment m' and cam projection n' , being 25 properly situated for that purpose, as shown in Figs. 1, 3, and 4, so that as the lever i' is partially rotated on the pin l' the slide l^2 is caused to travel back and forward at each 30 vibration of the lever i' the amount due to the amount of projection that the cam projection n' extends beyond the remainder of the segment m' , unless it is in a manner prevented 35 from so doing, as will be hereinafter described.

On a projection, k^3 , of the upper surface of the slide l^2 are pivoted two pawls, l^3 and m^3 , one of which is a little shorter than the other. 35 These are each actuated by a spring, n^3 , the springs being attached to the sides of the projection k^3 , the whole being arranged so that the pawls l^3 and m^3 press inward to grip upon 40 the serrated peripheral rings formed on the body of the nipper-rod or tongs, in the manner hereinafter described.

o^3 is a guide-plate attached, as shown, on one side of the bearing b' , receiving in a suitable groove formed in it the outer portion, p^3 , of 45 the segmental rack h' , for the purpose of guiding and rendering the lever i' perfectly steady transversely during its vibrations.

The nipper-rod or tongs consist of a pair of spring-jaws, q^3 , mounted on a rod, r^2 . (See 50 Figs. 5 and 19.) The force of the jaws q^3 , to nip the nail-plate f^2 , is augmented by forming them slightly tapered and providing them with a slip-collar, r^3 , to be used in the well-known ordinary way.

55 The rod r^2 is provided with peripheral serrations s^3 throughout a large portion of its length, as shown, and with a collar, t^3 . (See Figs. 1, 3, and 19.) The nipper-rod or tongs, with the nail-plate f^2 held by it, are placed in 60 position as shown, the nail-plate f^2 being received within the cylinder c' , and held and guided by the nose-piece d' at the end of the cylinder, while the rod r^2 of the nipper-rod or tongs is placed in the space q^2 , between the heads p^2 and pawls l^3 and m^3 , (see Figs. 4, 11, and 18,) so that the pawls l^3 and m^3 are enabled to act upon the serrations or rings s^3 ,

and as the slide l^2 moves forward they slip over the serrations s^3 ; but as the slide l^2 moves backward the pawls engage with the serrations s^3 and move backward the nipper-rod or tongs, thereby moving backward or feeding out the nail-plate f^2 from the nose-piece d' , to be acted upon by the cutters d and f , in a manner which will be readily understood by reference to Fig. 3. By making the pawls l^3 and m^3 of unequal length, as shown, (see Fig. 18,) they give a smaller or finer graduated feeding action of the nipper-rod or tongs.

a^4 is the ordinary stop-bar, with which 80 nearly if not all cut-nail machines are provided. This is technically called the "nipper-gage." One of its objects and purposes is to govern the amount that the nail-plate is passed in between the cutters d and f . The 85 one shown and marked a^4 is substantially similar to those which are and have been long in use. Therefore it need not be further described.

The operation of my invention is as follows: 90 The parts above mentioned having been constructed and arranged together as described and shown, and the moving parts put in motion in the ordinary manner, it will be seen that at each descent of the cutter d , held in 95 the cutting-jaw c , the lever l makes one complete vibration up or down. This causes, through the connecting-rod p' , a vibration of the segmental lever i' . Each vibration of the segmental lever i' causes a half-revolution of 100 the cylinder c' . This is so timed that when the segmental lever i' is at either end of its vibration the nail-plate f^2 is fairly lying on the cutter f , as shown in Fig. 3. Therefore, when the segmental lever i' is in a midway position 105 of its vibrations, the cylinder c' will hold the plate f^2 in a position at right angles to the cutter f . In this position it is shown in Fig.

1. The vibrations of the segmental lever are transmitted, through the connecting-rod t' , 110 arm v' , rock-shaft s , arm e' , and connecting-rod c^2 , to the frame a' , causing it to rotate slightly upon the pivot t , thereby providing for the necessary motion up and down to enable the cylinder c' and plate f^2 to be raised clear of the 115 die f as the cylinder and plate turn over; and not only to do this, but from the relative location of the pivot t with regard to the frame a' it causes the frame a' and all the parts attached thereto to swing bodily forward a 120 small amount as the cylinder c' rises to the position shown in Fig. 1, and swing bodily backward an equal amount as the cylinder c' descends to the position shown in Fig. 3.

Before proceeding further with this 125 description of the operation I wish here to remark that it has been hereinbefore described, and, as shown in the drawings, the front end of the cylinder c' is provided with beveled gear-teeth e' , extending around the whole of 130 its circumference. It is not necessary that the gear-teeth e' should extend the whole way round the circumference, because it is only necessary for the cylinder c' to be made to re-

volve a half-revolution. Therefore it is only necessary to provide it with such gear-teeth e' as are necessary for such half-revolution. When, however, the cylinder c' is provided 5 with gear-teeth all around, should the teeth in the one half of the circumference be worn or impaired from any cause, the cylinder may be turned over and the teeth in the other half of the circumference engaged with the teeth f' of the segmental rack h' .

Returning now to the operations of the parts, while the above-described operations of the frame a' and its attachments are taking place, the segment m' , situated on the front end of 15 the segmental lever i' , is being vibrated up and down, causing the cam projection n' , through the roller i^3 and pin h^3 , to operate the slide l^2 , carried in the rest g^2 , which it does in the following manner: When the cam projection n' is in contact with the roller i^3 , the slide l^2 and pawls l^3 and m^3 are moved forward or in 20 the direction of the arrow marked 1 in Fig. 4. The amount that the cam projection n' presses forward the slide l^2 the spring d^3 is compressed to allow this motion, and the spring d^3 remains compressed during the period occupied by the passing of the cam projection n' , which, it will be observed, is of considerable length. As soon as the cam projection n' has passed, as it does at the end of 25 each vibration of the lever i' , the force of the spring d^3 causes the slide l^2 to move rearward or in the direction indicated by the arrows 2 in Figs. 3 and 5, thereby causing the pawls l^3 and m^3 to move rearward the nipper-rod or 30 tongs r^2 , and consequently pushing out the nail-plate f^2 , or, in other words, feeding out the plate f^2 from the nose piece d^2 . The cam projection n' is made to project slightly more 35 than the amount required to give the necessary feed required for the nail-plate f^2 . The backward travel of the slide l^2 is governed by the end of the nail-plate f^2 coming in contact with the stop-bar or nipper-gage a^4 , thereby 40 holding the roller i^3 at a short distance from the periphery of the segment m' , the stop-bar or nipper-gage a^4 being enabled to do this because the feed motion is solely depending on the action of the spring d^3 . The part of the 45 nipper-rod or tongs r^2 placed between the projections n^2 is held with sufficient force and friction by the heads p^2 in the space q^2 , (see Figs. 10 and 11,) to prevent the nipper-rod or tongs from being drawn forward by the forward 50 movement of the pawls l^3 and m^3 , and to overcome, also, any tendency of displacement of the nipper-rod or tongs by the movements of the frame a' and its attachments. The feeding of the nail-plate f^2 takes place each time the 55 nail-plate and nose-piece d^2 of the cylinder c' are brought to the position shown in Fig. 3—that is to say, each time the nail-plate is laid fair on the cutter f , and preceding, by an instant of time, the moment at which the cutter f will be brought down upon it and sever a 60 piece therefrom to form a nail.

With regard to the cam projection n' , in case

it should be desirable in certain machines to provide this in such form that it may be adjustable either in length or position, Figs. 20, 70 and 21, and 22 are given; here the cam projection n' is made in two pieces, n^5 , attached upon the periphery of the segment m' by pins n^6 , passing through slotted holes n^7 , formed in them. The two parts are connected by an overlapping tongue-joint, n^8 , so that should they be moved apart for the purpose of increasing the length of the cam projection the continuous bearing for the roller i^3 to travel on (see Fig. 3) may not be destroyed thereby.

I prefer to use the cam projection n' in the manner hereinabove described—that is to say, in connection with the stop-bar or nipper-gage a^4 , which latter positively governs the feed of the nail-plate, and not the motion of 85 the slide l^2 , actuating the nipper-rod or tongs r^2 ; but as in case of certain classes of work it should be desired to dispense with the stop-bar or nipper-gage a^4 and feed by the motion of the slide l^2 , then I form the forward end of 90 the segmental lever i' as shown in Fig. 8 or 9.

In Fig. 9 a cam-link, b^7 , is formed, in which the roller i^3 travels in the ordinary well-known manner; or, instead of the complete link shown in Fig. 9, a partial link, b^8 , may be formed, as 95 shown in Fig. 8. In this case it will be readily understood that the nipper-rod or tongs r^2 will be moved to feed the nail-plate "positively" the amount of the cam projection n' for each piece cut of the nail-plate.

With regard to the nipper-rod or tongs, it will be observed that the serrations s^3 are not carried close up to the collar t^3 , but that a blank space, t^4 , is left. This is for the purpose that when the feed of the nail-plate has been 105 carried far enough the pawls l^3 and m^3 are prevented from feeding farther on account of there not being any serrations for them to act upon. The collar t^3 , also coming in contact with the plate f^2 or any other projection arranged for that purpose, also prevents the feed of the nail-plate being carried too far.

What I claim, and wish to secure by Letters Patent, is as follows:

1. In combination with a nail-cutting machine, the swinging frame a' , partially-rotated cylinder c' , segmental lever i' , having segmental rack h' , segment m' , and cam projection n' , slide l^2 , having pawls l^3 and m^3 , spring d^3 , and nipper-rod or tongs r^2 , the whole substantially as described.

2. The combination, with a nail-cutting machine, of the vibrating lever l , operated by the nail-machine, as described, connecting-rod p' , segmental lever i' , connecting-rod t' , arm v' , rock-shaft s , arm e^2 , and connecting-rod e^2 , with the frame a' , having its pivot-point t located as described, the whole substantially as described.

3. In combination with the slide l^2 , operated as described, and having pawls l^3 and m^3 , the rest g^2 , having gripping and friction heads p^2 , nipper-rod or tongs r^2 , having serrations s^3 , and jaws q^3 , the whole constructed and ar-

ranged substantially as described, for the purposes set forth.

4. In combination with the slide t^2 , operated as described, and having pawls l^3 and m^3 , the rest g^2 , having gripping and friction heads p^2 , nipper-rod or tongs r^2 , having serrations s^3 and jaws q^2 , blank space t^4 , and collar t^5 , the whole constructed and arranged substantially as described.

10 5. The improved nipper-rod consisting of the jaws q^3 , rod r^2 , serrations s^3 , blank space t^4 , and collar t^5 , combined with the slide t^2 ,

pawls l^3 and m^3 , and plate f^3 , operated as described, the whole substantially as set forth.

6. The combination of the segmental lever i^5 , operated as described, having segment m^1 , cam projection n^1 , slide l^2 , spring d^3 , pawls l^3 and m^3 , and nipper-rod or tongs r^2 , the whole substantially as described.

RANDOLPH HERSEY.
